DESIGN FOR A COMBINED HOE AND WEEDER HEAD

Clyde W. Busby, Dixmont, Pa.

Application November 8, 1944, Serial No. 116,214

Term of patent 3½ years

(Cl. D35—2)

To all whom it may concern:

Be it known that I, Clyde W. Busby, a citizen of the United States, residing at Dixmont, in the county of Allegheny and State of Pennsylvania, have invented a new, original, and ornamental Design for a Combined Hoe and Weeder Head, of which the following is a specification, reference being had to the accompanying drawing, forming a part thereof.

Figure 1 is a side elevational view of a combined hoe and weeder head, showing my new design;

Figure 2 is a top plan view; and

Figure 3 is an end elevational view thereof.

I claim:

The ornamental design for a combined hoe and weeder head, as shown.

CLYDE W. BUSBY.
